UNITED STATES PATENT OFFICE.

CLYDE S. WRIGHT, OF TOLEDO, OHIO, ASSIGNOR TO THE NATIONAL SUPPLY COMPANY,
OF TOLEDO, OHIO, A CORPORATION OF OHIO.

ROTARY DRILLING-MACHINE.

1,131,100.

Specification of Letters Patent.

Patented Mar. 9, 1915

Application filed February 24, 1914. Serial No. 820,554.

To all whom it may concern:

Be it known that I, CLYDE S. WRIGHT, a citizen of the United States, residing at Toledo, in the county of Lucas and State of Ohio, have invented new and useful Improvements in Rotary Drilling-Machines, of which the following is a specification.

My invention relates to rotary drilling machines but more specifically it relates to improvements in the means for mounting, controlling and operating the screws by which the roller gripping jaws are operated.

Some of the objects of this invention are to provide hand wheels for the said screws; to provide angular hubs for the hand wheels so that a wrench can be used to turn the screws; to provide a driving fork for each screw so constructed as to allow a maximum life of the gripping jaws without losing driving connection with the rotary table; to provide removable means for locking the screws to the driving forks so as to prevent the rotation of the screws; and to provide an improved means for removably locking the nuts or sleeves which work on the said screws so that the screws may be rotated in the nuts or sleeves.

Other objects will appear hereinafter.

Referring to the drawings, Figure 1 is a plan of a rotary table equipped with my invention; Fig. 2, a side elevation of Fig. 1 with parts in section; Fig. 3, an elevation of the upper part of Fig. 1 looking toward the left; Fig. 4, a section on the line IV—IV of Fig. 2; Fig. 5, a section on the line V—V of Fig. 4; Fig. 6, an elevation of a driving fork with the shaft of the screw shown in section; Fig. 7, an enlarged end elevation of one of the jaw-adjusting screws and the nut or sleeve coöperating therewith together with the sleeve locking device; Fig. 8, an elevation looking at Fig. 7 toward the left; Fig. 9, an elevation of the sleeve locking device and adjacent parts; Fig. 10, a side elevation of the sleeve locking device; Fig. 11, a vertical longitudinal section through the axis of the said sleeve, the screw being shown in side elevation in the sleeve; Fig. 12, a section on the line XII—XII of Fig. 11; and Fig. 13, a section on the line XIII—XIII of Fig. 2.

On the drawings, 1 is a rotary horizontal table driven by the bevel gearing 2 and supported on rollers (one marked 3 being shown) supported by the base 4.

The horizontal parallel screws 5 are supported on the table at opposite sides of its center. The table is provided at opposite sides of its center with the sockets 6 in which the lower ends or stems 7 of the driving forks 8 are mounted so that the latter may both oscillate and reciprocate in the sockets. The driving forks have above the stems 7 the vertical slots 9 to receive the shanks 10 of the screws 5. The screws each have the fixed collar 12 engaging one face of the adjacent fork 8. The other face of each fork 8 is engaged by the hexagonal hub 13 of the hand-wheel 14 secured to the associated screw 5. One end of each screw has right-hand threads and the other left-hand threads. The outer ends of each screw have square or angular portions 15, to which a wrench or crank can be applied to turn it. A wrench may be applied to the angular hub 13 for the purpose of turning the screw. Each driving fork 8 is provided with a central vertical hole 16 to receive the locking pin 17, which may be passed down through the hole 18 in the shank 10 to lock the screw 80 to the fork and prevent the former from rotation.

At right angles to the screws 5, I arrange the two bars or carriers 19 for the roller grips 20, one bar being at each side of the center of the table, each carrying a pair of grips arranged to engage the sides of the pipe 21 in a well-known manner. The ends of the carriers are all constructed alike so that a description of one will suffice for a description of all. On Figs. 12 and 13, I show the end of one carrier 19. The said end is provided with a pair of horizontal projections or extensions 22 and 23, one continuous with the upper part of the carrier, and the other with the lower part thereof, whereby a considerable space is left between the projections 22 and 23 for the swivel devices. The lower face of the projection 22 is provided with the short vertical cylindrical swivel-bearing 24 and the upper face of the projection 23 is provided with the short vertical cylindrical swivel-bearing 25, the bearings 24 and 25 being in vertical alinement. A swivel-block 26, divided into lateral halves 27 and 28 by a plane at right angles to the screws 5, has at its ends recesses 29 to receive the bearings 24 and 25 and constitute bearing boxes therefor. The block 26 has a round horizontal opening 110

therein to receive the body of the sleeve-nut 31, having the flange 32 bearing against the outer face of the section 27 and provided with notches 33 to receive the spring-actuated pin 34 seated in a hole in the sections 27 and 28, the said pin locking the sleeve-nut in any selected axial adjustment thereof. The inner end of the sleeve-nut 31 is provided with the washer 35 which rests against the outer face of the section 28, the nut 36 being screwed on the threads 37 on the end of the sleeve-nut 31 and against the washer 35. The outer end of the sleeve-nut 31 is provided with a squared portion 38 by 15 which it may be rotated. The sleeve-nuts 31 are all internally threaded and work on the threads of the screws 5 which extend through them. These sleeve-nuts have several oil-holes 39' which receive oil from the 20 ducts 39 in the sections 27 and 28 and convey it to the screws 5.

The outer end of each locking-pin 34 has the projection 40 extending at a right angle from the body of the pin, which is in a hole 25 41. The inner end of the hole 41 contains the expansion spring 42 which continually urges the pin 34 outwardly. The projection 40 may be swung up or down from its central, that is, horizontal position, so as to 30 lie beneath the flange 32 and in the recess 43 in the outer end of the section 27 of the swivel-block 26. When the projection 40 lies beneath the flange 32 and in the recess 43 (Figs. 3 and 8), the sleeve-nut 31 can 35 be rotated by applying a wrench or other tool to the angular end 38 thereon. If the projection 40 be swung to a horizontal position or in line with the radius of the sleeve-nut (Figs. 7 and 11) the outer end of the 40 pin 34 will be forced out by the spring 42 into any notch 33 which may happen to be opposite the pin or which may be brought opposite thereto. When the pin 34 is in a 45 notch 33 the sleeve-nut which carries the said notch is locked from rotation. The outer end of the pin 34 is beveled as shown at 44 to facilitate its entrance into the notches.

When the pins 17 are inserted through the 50 driving forks 8 and the screw-shank 10, and the projections 40 are swung beneath the flanges 33, the bars 19 may be moved one way or the other, causing the roller grips 20 to engage or release the pipe 21. 55 When the pins 17 are removed and the pins 34 are disposed so as to lock the several sleeve-nuts from rotation, the screws 5 may be rotated by applying a wrench or the like to the ends 15 of the screws, whereby the 60 bars 19 may be moved toward or away from each other so as to cause the roller grips 20 to engage or release the pipe 21. The screws may also be rotated by the hand-wheels 14 or by wrenches or the like applied to the angular hubs 13. It is seen that, 65

if one of the screws 5 is rotated, two of the ends of the carriers 19 will be brought toward or away from each other without it being necessary to turn the other screw 5 at the same time or at the same speed. By 70 mounting the screws 5 in the vertical slots 9 in the driving forks 8, I permit the screws to have a large amount of vertical travel with the bars 19 and grips 20 in addition to the vertical travel thereof permitted by the 75 stems 7 in the sockets 6 without danger of lifting the stems entirely out of the sockets and thereby severing the driving connections between the table 1 and the screws 5.

Modifications of the details and combinations thereof herein described may be made without departing from the spirit of my invention.

I claim—

1. In a rotary drilling machine, a rotary 85 table, a pair of opposed gripper carriers thereon, a pair of opposed screws for moving the carriers toward and away from each other, rotary sleeve-nuts for the screws carried by the carriers, means for rotating the screws, 90 said sleeve nuts provided with means whereby they may be rotated, means for releasably preventing the rotation of the screws, and means for releasably preventing the rotation of the sleeve-nuts. 95

2. In a rotary drilling machine, a rotary table, a pair of opposed gripper carriers thereon, a pair of opposed screws for moving the carriers toward and away from each other, and a driving-fork for each 100 screw, comprising a stem carried by the table and a vertically slotted upper end, the screws being seated in the slots in the respective driving-forks and vertically movable therein. 105

3. In a rotary drilling machine, a rotary table, a pair of opposed gripper carriers thereon, a pair of opposed screws for moving the carriers toward and away from each other, a driving-fork for each screw, comprising a stem carried by the table and having a vertically slotted upper end, the screws being seated in the slots in the respective driving-forks, and means for locking each screw and its respective driving-fork together. 110 115

4. In a rotary drilling machine, a rotary table, a pair of opposed gripper carriers thereon, a pair of opposed screws for moving the carriers toward and away from each other, a driving-fork for each screw, comprising a stem carried by the table and having a vertically slotted upper end, the screws being seated in the slots in the respective driving-forks, and a locking pin extending vertically through the slot in each driving-fork and through its respective screw for locking each screw and its respective driving-fork together and permitting the screw to reciprocate vertically. 120 125 130

5. In a rotary drilling machine, a rotary table, a pair of opposed gripper carriers thereon, a pair of opposed screws for moving the carriers toward and away from each other, a driving-fork for each screw, comprising a stem carried by the table and having a vertically slotted upper end, the screws being seated in the slots in the respective driving-forks, and means for locking each screw and its respective driving-fork together, so that the screw cannot rotate but may reciprocate vertically.

6. In a drilling machine, a pair of opposed gripper carriers, a pair of screws for moving the carriers toward and away from each other, rotary sleeve-nuts for the screws carried by the carriers, the sleeve-nuts being provided with a circular series of notches, and a spring-pressed rotatable pin adapted to enter any one of the notches when in line therewith, the said pin having

a means for preventing the entrance of the pin into a notch in line therewith.

7. In a drilling machine, a pair of opposed gripper carriers, a pair of screws for moving the carriers toward and away from each other, rotary sleeve-nuts for the screws carried by the carriers, the sleeve-nuts being provided with a circular series of notches, and a spring-pressed rotatable pin adapted to enter any one of the notches when in line therewith, the said pin having a lateral projection adapted to lie beneath the flange and thereby prevent the pin from entering any notch.

Signed at Toledo, Ohio, this 21st day of February A. D. 1914.

C. S. WRIGHT.
